N. W. Stearns

Inventor,
Oliver F. Sage

UNITED STATES PATENT OFFICE.

OLIVER F. SAGE, OF BOSTON, MASSACHUSETTS.

DESIGN FOR ADVERTISING-WAGONS.

Specification forming part of Design No. 7,935, dated December 15, 1874; application filed December 4, 1874.
[Term of Patent 14 years.]

To all whom it may concern:

Be it known that I, OLIVER F. SAGE, of Boston, in the county of Suffolk and State of Massachusetts, have invented a new Design for an Advertising-Carriage, of which the following is a full, clear, and exact description, reference being had to the accompanying photograph, making part of this specification.

In the said photograph, A represents the ordinary running-gear of a carriage, on which is placed a hollow body, B, made in the form of a traveling-trunk, to the top of which is secured a strip, a, having my advertisement—"Sage's, 546 Washington Street"—thereon. Upon the projecting front b of the carriage is placed transversely a valise, C, which forms the seat for the driver, and at each end of the valise is a traveling-bag, D, the two bags D

D forming the sides of the seat. On the rear end of the trunk is again displayed the name and place of business, viz: "Sage's Trunk Depot, 546 Washington St."

What I claim as my invention, and desire to secure by Letters Patent, is—

The design for an advertising-carriage, consisting of the body B, in the form of a traveling-trunk, supported on a carriage-gear, and provided with a driver's seat, formed of a valise, C, having a traveling-bag, D, at each end, substantially as shown and described.

Witness my hand this 2d day of December, 1874.

OLIVER F. SAGE.

In presence of—

P. E. TESCHEMACHER,
N. W. STEARNS.
